United States Patent Office

Des. 211,228
Patented May 28, 1968

211,228

ELECTRIC SHAVER

Gotz Florian Strzelczyk, Mulheim (Main), Germany, assignor to Sunbeam Corporation, Chicago, Ill., a corporation of Illinois

Filed Mar. 17, 1967, Ser. No. 6,272

Term of patent 14 years

(Cl. D95—3)

Fig. 1.

Fig. 2.

Fig. 3.

Fig. 4.

Fig. 5.

Fig. 6.

FIG. 1 is a front perspective view of an electric shaver showing my new design;

FIG. 2 is an elevational view thereof on an enlarged scale of the side opposite that shown in FIG. 1;

FIG. 3 is a top plan view thereof;

FIG. 4 is a left end elevational view thereof;

FIG. 5 is a right end elevational view thereof; and

FIG. 6 is a bottom view thereof.

The dominant features of the design reside in the portions shown in full lines on the drawing.

I claim:

The ornamental design for an electric shaver, as shown and described.
